CLAIM

The ornamental design for a heating container, as shown and described.

DESCRIPTION

FIG. 1 is a perspective view of a heating container showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The dashed-dot lines shown in FIG. 5 represent an unclaimed border between claimed and unclaimed subject matter. The white areas within the perimeters defined by the dashed-dot lines represent environmental subject matter and form no part of the claimed design.
